SOUND RECORDING SYSTEM

Percy R. Glenn, Los Angeles, Calif., assignor to
Ubbe B. Iwerks, Los Angeles, Calif.

Application July 22, 1935, Serial No. 32,567

2 Claims. (Cl. 179—100.3)

This invention relates to an improved system for recording acoustic waves upon a light sensitive film.

The general object of the invention is to provide an improved means for controlling the action of a light valve.

A feature of the invention resides in the employment of constant currents of high frequency in the circuit controlling the mean recording position of a recording device.

Another feature of the invention resides in modulating the high frequency currents and controlling the output of the modulator by a direct current potential which is the product of the envelope of the signal currents.

An additional object of my invention is to provide a novel method of recording signal currents on a recording medium.

Other objects and the advantages of this invention will be apparent from the following description taken in connection with the accompanying drawing.

The accompanying drawing is a diagrammatic disclosure of my improved sound recording device.

Referring to the drawing by reference characters I have indicated my improved sound recording system generally at 10. A light source is shown at 12. From this source light is focused by a lens system 13 on apertures 14 which are located in the pole pieces of a permanent magnet 15. The light is then focused by a lens system 16 through an aperture 17 in a guide 18. A film 19 passing over sprockets 20 is subjected to light which passes through the aperture 17. Flat conductors 21 and 22 arranged in the field of the magnet 15 constitute a light transmitting slot. The width of the slot formed between the conductors 21 and 22 affects the exposure of the film 19 to the light from the source 12.

The recording device thus briefly described is well known in the art and I do not wish to be limited to the use of this particular form of recording device.

Sound waves detected by the microphone 23 are suitably amplified in the usual amplifier unit 24 from which a portion of the signal currents pass through wires 25 and 26 to the input of a standard type amplifier unit which is diagrammatically shown and is enclosed by the dotted lines 27.

The output of the amplifier 24 is applied through wires 28 and 29 to the primary winding 34 of a transformer 35. The secondary winding 36 of the transformer is connected by wires 37 and 38 to the flat light valve conductor members 21 and 22. The wire 38 has a potentiometer 39

interposed therein. Thus it will be seen that a portion of the signal currents from the secondary winding 36 of the transformer 35 flows through the wire 37, through the conductors 21 and 22 and through the wire 38 back to the transformer 35.

The magnetic field due to the signal current flowing in the conductors 21 and 22 will react with the constant field due to the magnet 15 and cause the conductors 21 and 22 to vibrate and vary the width of the light transmitting slot in accordance with the instantaneous variations in the signal currents.

At 40 I have indicated diagrammatically a standard type electron coupled high frequency oscillator the output of which is impressed on the primary winding 41 of a transformer 42 of a push-pull modulator 43. The output of the modulator 43 is impressed on the primary winding 44 of a transformer 45 of an amplifier unit 46 and the output of the amplifier unit 46 is impressed on the primary winding 47 of a transformer 48. The secondary winding 49 of the transformer 48 is connected by wires 50 and 51 to a full wave rectifier 52.

I may provide a bridge which includes terminals 54, 55, 56, 57, 58, and 59. The terminal 58 of the bridge is connected by a wire 60 to one side of an "A" battery 61 or other source of constant voltage and the terminal 59 is connected by a wire 62 to the other side of the battery 61.

The output of the rectifier 52 is connected by a wire 63 to the bridge terminal 54 and has interposed therein a choke coil 64 and a milliammeter 65. The choke 64 prevents the passage of any undesirable high frequency currents which might come from the oscillator 40. The center tap of the secondary winding 49 of the transformer 48 is connected by a wire 66 to the terminal 55 of the bridge 53. The bridge terminal 57 is connected by a wire 67 to the center tap of the secondary winding 36 of the transformer 35 and the bridge terminal 59 is variably connected as at 68 to the potentiometer 39 by a wire 69. The potentiometer 39 is provided to balance the winding 36 and provide a center tap connection. In certain installations the bridge 53 may be omitted if desired. In this case the wire 63 would be directly connected to the wire 69 and the wire 66 would be directly connected to the wire 67.

The secondary winding 70 of the transformer 31 is connected by wires 71 and 72 to a full wave rectifier 73, the output of which is connected by a wire 74 to one side of a condenser 75 and has interposed therein a choke coil 76. The center

tap of the secondary coil 70 of the transformer 31 is connected by a wire 71 to the other side of the condenser 75. The wire 71 is connected as at 78 to one end of a resistor 79. The opposite end of 5 the resistor 79 is connected to the wire 74 as at 78' and is connected by a wire 80 to the grid resistors 81 of the push-pull modulator 43 and to the secondary winding 82 of the transformer 42. Furthermore the wire 77 is variably connected as 10 at 83 to the potentiometer 84 of the push-pull modulator 43. By adjusting the potentiometer 84 the amount of bias which is to be applied to the conductors 21 and 22 may be set at any desired maximum value. The condenser 75, choke 76, 15 and resistance 79 form a filter system which together with the electron coupled oscillator 40 and the push-pull amplifier 43 results in a biasing current which is very free from instantaneous signal currents. As shown the oscillator 40 includes 20 an output resistance 86 and an output potentiometer 87. A wire 88 connects the arm of the potentiometer 87 to the primary 41 of the transformer 42.

The potentials necessary to operate the amplifier 27, the oscillator 40, the modulator 43, and the amplifier 46 are supplied by the customary batteries 85^a, 85^b, and 85^c.

The operation of the invention is as follows: The high frequency oscillator 40 produces a supply of constant frequency and voltage a portion of which, as determined by the setting of the potentiometer 87, is impressed on the grids of the pair of push-pull tubes of the modulator 43. The output of these push-pull tubes is controlled by a 35 direct current potential which is the envelope of the detected signal currents and is produced by amplifying a portion of the signal currents as at 27 and then rectifying said portion of the signal currents as at 73. The potential so produced is applied across the condenser 75 and the resistance 79.

This direct current potential is used to bias the push-pull tubes to control their output in propor-

tion to the envelope of the signal currents. The output of the push-pull modulator is further amplified by the amplifying unit 46 and then rectified as at 52. This rectified current is used to unbalance the bridge circuit and allow the direct current voltage of the battery 61 or other constant source of direct current potential to displace the light valve in accordance to the amplitude of the signal currents. 5

From the foregoing description it will be apparent that I have provided a novel sound recording system which is simple in construction and highly efficient in use.

Having thus described my invention I claim:

1. In a circuit for controlling a sound recording device, a source of signal current, an amplifier for said signal current, means to rectify and partially filter said signal current, a high frequency oscillator having a constant output which is independent of external circuit conditions, a push-pull modulator including a pair of grids, means to supply a small portion of the output of said high frequency oscillator to said modulator, means to apply said rectified signal current to both of said grids in the same phase whereby the unfiltered signal is suppressed and the signal amplitude component is applied as a bias to said modulator, an amplifier associated with said modulator and adapted to amplify the output thereof, and a rectifier to rectify the output of said amplifier. 15 20 25

2. In a circuit for controlling a sound recording device, a source of signal current, an amplifier for said signal current, means to rectify and partially filter said signal current, a high frequency oscillator, a modulator including a pair of grids, 35 means to supply a portion of the output of said high frequency oscillator to said modulator, means to apply said rectified signal current to both of said grids in the same phase whereby the unfiltered signal is suppressed and the signal amplitude component is applied as a bias to said modulator, and a rectifier to rectify the output of said modulator. 40
